HYDRAULIC TELECONTROL DEVICE

Hugh Graham Conway, Warrington, England, assignor to Aeronautical & Mechanical Investments Limited, a British company

Application March 30, 1942, Serial No. 436,909
In Great Britain April 2, 1941

7 Claims. (Cl. 60—54.5)

This invention comprises improvements in or relating to hydraulic tele-control devices.

A type of hydraulic tele-control apparatus is known in which a transmitting station comprises two cylinders and pistons connected respectively to two pipe lines and a receiving station comprises two other cylinders and pistons into which the pipe lines deliver so that the receiving pair of pistons are forced to copy the movements of the transmitting pair. The pistons being connected by appropriate links to levers mounted on the transmitting and receiving apparatus, movement of the lever at the transmitting end will be copied by the movement of the lever at the receiving end of the apparatus.

In apparatus of the kind described it is only possible to transmit motion in one phase, that is to say, a to-and-fro motion, but in many cases in aircraft, members are mounted so as to have a universal movement about a centre and thus to be capable of a compound movement. In other cases there may be instances where it is desirable to transmit desired movements to or from more than one control member. To enable such cases to be met the present invention contemplates what may be described as a polyphase hydraulic transmission.

The present invention comprises in a hydraulic tele-control system the combination of three or more transmission pipes connected at one end of the system to a transmitting (or receiving) station having compression devices and a single actuating member with a compound freedom of movement operatively connected to the compression devices so that the phases of movement of the actuating member correspond to phases of liquid movement in the pipes, said pipes being connected at the other end to a receiving station (or transmitting station if the first-mentioned end of the system is the receiving end) said station having compression devices and one or more actuating members linked to the compression devices so that their phases of movement are compelled to correspond to the phases of movement of the actuating member at the other station.

It is to be understood that the expressions "one end of the system" and "the other end of the system" are to be taken broadly as meaning the operative ends of the system for the purpose of the tele-control under consideration. There may be branches in such a system or the pipes may run beyond the "end" for purposes special to a particular installation. For example, it is known that a single phase system may have two or more transmitting stations and it would be within the

scope of the present invention to provide in a parallel way two or more transmitting stations in a polyphase system according to the present invention, and either of the transmitting stations would be regarded as being at an "end" of the transmission pipes.

In practice the "compression devices" normally consist of pistons working in cylinders but it is to be understood that the term includes other equivalent devices such as bellows and the like.

In the preferred form of the apparatus according to this invention the system comprises three transmission pipes and three compression devices at the first-mentioned transmitting (or receiving) station and the actuating member consists of a lever pivoted in the centre of the three compression devices so as to have a universal movement about said centre.

Further features of the invention will appear from the following description, which is given by way of example, of specific embodiments of apparatus in accordance with the invention.

In the drawings—

Figure 1 is a diagram of one form of apparatus in accordance with the invention showing a transmitting and receiving station and interconnecting pipes;

Figure 2 is a vertical section through a transmitting apparatus taken on the line 2—2 of Figure 3;

Figure 3 is a plan of the same;

Figure 4 is a diagram of one possible alternative system; and

Figure 5 is a diagrammatic view of another alternative system.

Referring to Figure 1, 11 is a transmitting station and 12 a receiving station of a hydraulic tele-control apparatus in which the transmitting station is provided with three cylinders 13, 14, 15 grouped equidistantly around a central pivot 16. Upon the pivot 16 there is mounted for universal movement an actuating lever 17 having a handle 18 and, near the pivot, three radial arms 19, 20, 21 which are connected by piston rods 22 to pistons working in the cylinders 13, 14, 15. The cylinders are connected by transmission pipes 23, 24, 25 to the receiving station 12. At the receiving station 12 are three cylinders 26, 27, 28 containing pistons which are connected by connecting rods 29 to the three arms 30, 31, 32 of an actuating lever pivoted about a central universal pivot 33 and provided with an upstanding arm 34 for actuating devices which it is intended to control. Movement of the actuating lever 17 in one plane, say that indicated by the double-headed arrow 35 at

the transmitting station, will cause hydraulic fluid in the cylinder 13 to be expelled or drawn in, according to the direction of the movement while that in the cylinders 14 and 15 is moved in the opposite direction. At the receiving station the effect of expulsion of the cylinder 13 is to force liquid into the cylinder 26 and to cause as much lifting of the lever arm 31 as at the transmitting station there was depression of the lever arm 19. The cylinder 26 being disposed on the opposite side of the pivot 33 from that which the lever arm 19 occupies with respect to the pivot 16 the result is that the arm 34 of the lever at the receiving station moves over in an arc having the same direction of movement as the lever 17 and to the same extent. Movement in another plane, such as is indicated by the arrow 36, will correspondingly produce movement in the same plane by the lever 34 as shown by the arrow 37 and, in fact, movement in any intermediate planes will similarly be copied precisely both in direction and extent.

It will, of course, be clear that the apparatus as illustrated in Figure 1 is diagrammatic and that all the ordinary means of compensation for leakage, for variation of temperature and so forth which may be called for in apparatus of this kind should be provided.

The transmitting and receiving stations are similar to one another except that the actuating lever 17 at the transmitting station is provided with a handle and the corresponding lever 34 at the receiving station is provided with means such as a ball joint 38 to enable it to be connected to any member which it is intended to control. The detailed views shown in Figures 2 and 3 of the transmitting station will therefore serve as a receiving station also.

In Figures 2 and 3, 40 represents a casing which contains an internal space 41 acting as a liquid-reservoir and provided with a filling cap 42. In the casing are secured three cylinder bodies 13, 14, 15 which correspond to the cylinders of Figure 1 and are connected by appropriate union joints to pipes 23, 24, 25. The cylinder bodies have flanges 43 about the middle of their length which abut on the underside of the casing 40 and are clamped thereto by means of a clamping plate 44 secured in place by a central setscrew 45. Packing rings 46, 47 surround the joints which are made between the outsides of the cylinder walls and the casing 40 so that no leakage may take place from the reservoir 41. The casing is provided with fixing lugs 48, 49, 50 so that it may be secured in a suitable position, for example, close to the pilot's seat in an aircraft.

On top of the casing 40 there is a central up-standing forked lug 51 in which is pivoted at 53 the cruciform central member 52 of a Hooke's joint. The cross pivot of the member 52 is shown in dotted-lines at 54 and enters lugs 55, 56 on the lower end of a lever 17, which is thereby mounted for universal movement but is prevented from rotation relatively to the casing 40. The lever 17 has upon it radially projecting lugs 58, 59, 60 which are located at a spacing of 120° from each other around, and in the same plane as, the Hooke's joint 52 and which carry ball sockets 61 to receive the ends of the connecting rods 22.

The connecting rods 22 are jointed by ball joints 62 to pistons 63 one of which is shown in section in Figure 2. The pistons 63 are long cylindrical elements provided with packing rings 64, 65. In the central portion they are pierced transversely with a long slot 66 which serves to receive and to

work over a pin 67 fixed diametrically across the bore of the cylinder 13, 14 or 15 as the case may be. This prevents the piston from rotating. Furthermore, on either side of the slot the pistons have flats as shown at 68, 69 and the flats span ports 70 in the sides of the cylinders. The ports are covered with filter-gauze 71 which is exposed to the reservoir 41 and through the filter-gauze hydraulic fluid from the reservoir can enter the ports 70 and thence pass into the space within the cylinders which is provided by the flats 68, 69. From here the hydraulic fluid has access through passages 72, 73 to a light lift valve 74 mounted in the ends of each of the pistons 63 and held on its seating by a light spring 75. The effect is that if, through leakage or fall in temperature, a reduction takes place in the amount of fluid in the pipes 23, 24, 25 the fluid is made up from the reservoir 41, and it is impossible for the fluid pressure in any of the pipes to fall appreciably below atmospheric pressure so that entry of air through any leaks, which would spoil the operation is obviated.

In the apparatus described in Figures 1 to 3 the lever at the receiving end precisely copies the movement of the lever at the transmitting end. It is not, however, essential that this should be the case because it is possible, seeing that one of the levers has a compound movement, for the movement at the other end of the system to be provided by two separate levers, one of which copies movements of the lever at the other end in one phase or plane and the other of which levers copies movements of the lever at the other end in another phase or plane.

Referring to Figure 4, this shows a transmitting station comprising cylinders 13, 14, 15 and a lever 17 similar to the correspondingly numbered parts already described and similarly connected to transmission pipes 23, 24, 25.

At the other end of the system the pipe 23 is connected to a cylinder 88 and the pipe 25 to a cylinder 81. The cylinder 88 forms one of a pair, each of which contains a piston connected by a link 82 to the opposite ends of a lever 83 having an arm 84 for connection to any desired device. Similarly, the cylinder 81 forms one of a pair connected by links 82 to a lever 85 having an arm 86. The other cylinders of these two pairs, which are numbered 87, 88 in the drawings are connected together and to the line 24. The effect is that if the lever 17 be rocked about a line which passes through its pivot and its connection to the piston in the cylinder 13, the piston will remain at rest while the pistons in the cylinders 14 and 15 will one of them be moved in and the other one out. This will cause movement of the lever 86 at the receiving station while the lever 83 remains at rest. Alternatively, if the lever 17 is rocked about an axis which passes through the connection to the piston in the cylinder 15 then the piston in the cylinder 13 will be moved in conjunction with that of 14 and the lever 84 will be moved while 86 remains at rest. Therefore the lever 17 can be used to control two levers at the receiving station.

Alternatively, there might be two levers, such as 84, 86 at the transmitting station which between them control a single lever such as 17 at a receiving station. In this case it is assumed that the lever 84 is held at rest or locked when the lever 86 is operated, and the lever 86 is held or locked when lever 84 is operated.

Moreover, instead of a three-phase system as described, it is possible, as shown in Figure 5, to have at the transmitter four cylinders 88, 81,

92, and 93 operated by a lever 94 and working a two-phase system, and two of the cylinders 92 and 93 may be connected by a pipe 96 to a single common return line 99. The other cylinders 90 and 91 are connected respectively to the two lines 97 and 98. The lines 97, 98, and 99 are connected to a receiver of similar construction comprising four cylinders 100, 101, 102, and 103 connected to a lever 104. Lines 97 and 98 are connected to cylinders 100 and 103 respectively and the cylinders 101 and 102 to the common line 99. Again, there might be five or more cylinders, but the simplest embodiment of the invention would appear to be that which is illustrated in Figures 1 to 3.

In the following claims, the expression "a station" includes a transmitting station or a receiving station, thus in the case where there are two stations the first station may be a transmitting station and the second station may be a receiving station or vice versa.

I claim:

1. In a hydraulic tele-control system, the combination of a station comprising a member mounted so as to be capable of a compound freedom of movement, three compression devices grouped about the member symmetrically and operatively connected thereto so that movement of the member in any of the directions in which it is free to move produces compression in at least one of the compression devices and corresponding expansion in the remainder, three pipes connected one to each of the compression devices and extending to a second station, three fluid-actuated devices at the second station one in communication with each of the pipes, and a second member at the second station pivoted for rocking with a compound freedom of movement, the fluid-actuated devices at the second station being grouped about said second member symmetrically and operatively connected thereto, whereby movement of the member at one station in any one direction produces corresponding direction of movement of the member at the other station at least one of the members with a compound freedom of movement consisting of a lever mounted on a central pivot element for universal movement and, the three fluid-compression devices consisting of three parallel cylinders the axes of which are grouped about the central pivot element, three pistons being disposed in the cylinders, and connecting rods connecting the pistons to the lever.

2. In a hydraulic tele-control system, the combination of a station comprising a member mounted so as to be capable of a compound freedom of movement, three compression devices grouped about the member symmetrically and operatively connected thereto so that movement of the member in any of the directions in which it is free to move produces compression in at least one of the compression devices and corresponding expansion in the remainder, three pipes connected one to each of the compression devices and extending to a second station, three fluid-actuated devices at the second station one in communication with each of the pipes, and a second member at the second station pivoted for rocking with a compound freedom of movement, the fluid-actuated devices at the second station being grouped about said second member symmetrically and operatively connected thereto, whereby movement of the member at one station in any one direction produces corresponding direc-

tion of movement of the member at the other station at least one of the members with a compound freedom of movement consisting of a lever pivoted on a Hooke's joint so as to be capable of compound movement without being capable of rotation about an axis extending along the lever, the three fluid-compression devices consisting of three parallel cylinders the axes of which are grouped about the Hooke's joint, three pistons being disposed in the cylinders, and connecting rods connecting the pistons to the lever.

3. In a hydraulic tele-control system, the combination of a station comprising a single actuating member and a mounting therefor such that the member has a compound freedom of rocking movement, at least three fluid-compression devices grouped symmetrically about the member and operatively connected thereto so that rocking movement of the member in any direction corresponds to compression in at least one of the compression devices and corresponding expansion in at least one other, three pipes connected one to each of the compression devices and extending therefrom to a second station, a second station comprising at least three fluid-actuated devices each in communication with one of said transmission pipes and actuated means operatively connected to the fluid-actuated devices and capable of more than one movement positively controlled by the fluid actuated devices.

4. A hydraulic tele-control system as claimed in claim 3, wherein the actuating member consists of a lever mounted on a central pivot element for universal movement and the fluid-compression devices comprise cylinders having axes parallel to one another and grouped about the pivot point, pistons therein, and connecting rods operatively connecting the pistons to the lever.

5. A hydraulic tele-control system as claimed in claim 3, wherein the actuating member consists of a lever pivoted on a Hooke's joint so as to be capable of compound movement without being capable of rotation about an axis extending along the lever, the fluid-compression devices consist of cylinders having axes parallel to one another and grouped about the Hooke's joint, pistons therein, and connecting rods operatively connecting them with the lever.

6. A hydraulic tele-control system as claimed in claim 3, wherein the fluid-actuated devices at the second station consist of cylinders and pistons, and the actuated means consists of a lever mounted upon pivot means for universal movement in the center of the cylinders and pistons and operatively connected to the pistons by connecting rods.

7. A hydraulic tele-control system as claimed in claim 3, wherein the fluid-actuated devices at the second station consist of two pairs of cylinders and pistons therein and the actuated means consists of a plurality of levers, one lever located between and operatively connected to the pistons in one pair of fluid-actuated pistons and cylinders and the other lever being located between another pair of cylinders and operatively connected to the pistons therein so that one lever is operated by movement of the actuating member in one direction and the other lever is operated by movement of the actuating member in another direction two of the three pipes respectively connected with one cylinder of each pair and the third pipe connected to both of the remaining cylinders.
